DOOR SECURING DEVICE

Allen Chambers, Independence, and Roy E. Gearhart, Kansas City, Mo., assignors of one-third to W. E. Ludwig, Kansas City, Mo.

Application November 21, 1941, Serial No. 419,956

2 Claims. (Cl. 292—268)

This invention relates to improvements in a door securing device and has particular reference to a door securing device wherein the door is secured to the door jamb for a limited open position.

Door securing devices for securing the door in a limited open position, which are now in general use, consist of chains or hinged members which are secured to the door casing and door in such a manner that they are exposed within the room at all times and not only detract from the appearance of the structure, but also project from the structure to an objectionable degree; furthermore, the door securing device is operable only from inside the room.

This invention is an improvement over our pending application, Serial No. 409,230, filed September 2, 1941, and has for its principal object the provision of a door securing device wherein the principal parts of the device are disposed between the door and the door jamb when the door is closed and wherein the door securing device is operable from either inside or outside the room.

A further object of the present invention is the provision of a door securing device having means whereby the tenant cannot leave the door of his room closed when leaving the room without operating a key from outside the room to operate the securing device.

Another object is the provision of door securing means whereby the door is secured against opening from a predetermined partially open position and is also secured against accidental closing from said partially open position.

A further object of the present invention is the provision of a door securing device wherein an extension bar is mounted in a housing secured to the face of the door jamb, and adjustable means carried by the door to operably engage said extension bar and move it to the extended position as the door is moved from the closed to the partially open position.

Other objects are simplicity and economy of construction, ease and efficiency of operation, and adaptability for use with the various types of doors and to effect different degrees of opening.

With these objects as well as other objects which will appear during the course of the specification, in view, reference will now be had to the drawings wherein:

Figure 1 is an inside elevation of a portion of a door and its mounting frame having a door securing device embodying this invention.

Fig. 2 is a cross sectional view, taken on line 53

II—II of Fig. 1, with the door shown in the partially open position in dotted lines.

Fig. 3 is an outside elevation of a portion of the door and its mounting frame showing certain portions of the door securing device.

Fig. 4 is an enlarged view of the face of the door jamb with the extension bar and housing shown in position thereon and with parts broken away and with the extension bar in the closed position and extended in dotted lines.

Fig. 5 is an enlarged sectional view, taken on line V—V of Fig. 4 with the bar extended.

Fig. 6 is an enlarged sectional view, taken on line VI—VI of Fig. 1, with certain parts in elevation.

Fig. 7 is a horizontal sectional view, taken on line VII—VII of Fig. 6.

Fig. 8 is an elevational view of the bar housing.

Fig. 9 is an enlarged view of the operating lock and its connection with the operating gear partly in section.

Fig. 10 is an inside end elevation of the lock.

Fig. 11 is an end elevation of the operating gear.

Fig. 12 is an elevational view partly broken away of a modified form of the device with the extension bar shown in the normal position.

Fig. 13 is a horizontal sectional view, taken on line XIII—XIII of Fig. 12 with the bolt shown in the intermediate position to engage the door limiting bar.

Fig. 14 is an enlarged sectional view of a portion of the lock and operating gear.

Fig. 15 is a reduced sectional view taken on line XV—XV of Fig. 14.

Throughout the several views, like reference characters designate similar parts, and the numeral 20 is a door frame in which is mounted a door 22 for swinging movement on hinges 24. The door frame is secured to studs 26 and includes a door jamb 28 having its face 30 slightly spaced apart from the edge of the door when the door is in the closed position.

A door stop 32 secured to the face of jamb 28 serves as an abutment for the door whereby it is maintained in substantially flush relation with the inner edge of jamb 28 when the door is closed. The usual door casings 34 partially overlap the edge of jamb 28 and extend outwardly therefrom.

For securely holding the door in the partially open position for ventilation and for protection from intrusion when answering the door, the following door securing device is provided: The pre-

ferred form of this device is shown in Figs. 1-11, inclusive and includes a housing 36, having side walls 38 and 40, spaced apart with the inside wall offset and welded at certain points to the planar outside wall 40. The housing is open at its front edge 46. Side wall 40 which is normally adjacent the edge of door 22 is provided adjacent its upper end with a bight 42.

It will be noted that the width of housing 36 is substantially the thickness of the door 22 and it is morticed into jamb 28 so that the outer surface of wall 40 is in planar relation with the face 30 of the door jamb. The housing 36 is held in position by means of a counter-sunk screw 44 which is disposed flush with the outer surface of wall 38 and in alignment with opening 36 formed through wall 40 as clearly shown in Fig. 8. An offset portion 47 formed inwardly in wall 40, is directly opposite bight 42 formed in the outer housing wall 40 and extends transversely across the wall 38 to the front edge of the housing and may be slightly beveled or offset at 48.

The screw 44 is so positioned, relative to the hole 46 formed in the side wall 40, that it is not accessible therethrough when the extension bar 50, pivoted at 66 within said housing, is in the normal positions as shown in Fig. 4; however, when the extension bar is moved to the extended and completely raised position with the door wide open, the bar is moved from between hole 46 and the head of the screw so that the screw can be removed or set. A suitable screw 52 may be provided for securing the lower end portion of the housing against displacement.

It will be noted that the door jamb is recessed at 54 to receive the collar 56 formed in the wall 38 in horizontal alignment with the bight 42 formed in wall 40. This collar or flange 56 is vertical oblong, to compensate for sagging of the door and is snugly fitted into recess 54 to hold the housing 36 in position and against transverse movement when the limiting bar is in use.

Extension bar 50 is provided with a longitudinal slot 58 having an enlarged portion 60 at its upper end and outwardly disposed offset 62 at its lower end. The bar is downwardly tapered and rests against offset 64 of wall 38 when its outer edge is flush with the outer face of housing 36. The pivotal pin 66 of the extension bar 50 is slightly above bight 42 so that the pin 66 is definitely secured in both of the walls 38 and 40 as clearly shown in Fig. 5.

A tension spring 68 rigidly secured to wall 38 at 70 extends upwardly to engage extension bar 50 above pivot 66 thereby tending to urge the bar against offset 64 when the bar is in the normal position and also serves to urge the outer extremity of the bar 50 downwardly when the bar is in the extended position shown in dotted lines in Fig. 4. Other types of spring tension might be utilized for this same purpose without any material change in the general structure of the device.

One form of suitable adjustable means carried by the door for operatively engaging the extension bar 50 is shown in the form of a bolt 72 slidably mounted in a housing 74 which is inserted in a cylindrical recess 76 formed inwardly from the edge surface of the door. This housing is securely anchored by means of screws 78 which pass through housing plate 80. Bolt 72 is notched at 82 to provide a flattened surface 84 into which is cut notches to form transverse teeth 86 of sufficient number to permit a sufficient movement of the bolt to lock and unlock the door. The outer

end portion of bolt 72 is annularly grooved at 90 to form a bolt head 92.

Referring to Figures 6 and 7 reference is had to the specific means shown whereby the bolt 72 is operated from the inside of the room by means of a hand knob 94 and from the outside by means of a key 96. Axially secured by set screws 98 to knob 94 is a pinion or gear 100, which extends through a collar 102, hole 104 formed through door 22 and then through holes 106 formed through housing tube 74. The pinion when so positioned through housing 74 is in mesh with teeth 86, so that as it is rotated it will move the bolt 72 longitudinally to any of the desired positions.

The outside of door 22 is provided with a cylinder lock at 108 having a barrel 110 and a plug 112 into which is adapted to be inserted the key 96. This lock is of the well known standard type, such as the Yale or Corbin, and is best shown in Figures 7, 9, 10, and 11. This lock is positioned in a recess 116 formed in the door in axial alignment with the pinion 100.

The barrel 110 extends through an opening in plate 118 and is secured in the proper position relative thereto by a nut 120 which cooperates with threads 121 formed on barrel 110.

Placed between the head 122 and plate 118 is a spacing washer 124 of any suitable thickness to properly position the lock barrel relative to the housing 74. This lock is of a common type wherein the key can be removed from the lock at either end of its stroke thereby making it possible to either move the lock to the locking position or to the unlocking position and remove the key.

The operating connection between lock 108 and the pinion 100 is best shown in Figure 9. The inner end of the lock is provided with an annular ring 126 which is secured by threaded pins 128 to the plug 112. The outer ends of the pins 128 are reduced at 130 and are adapted to engage in holes 132 formed through annular friction plate 134, which is slidably mounted on the reduced end 136 to receive a compression spring 140 held under compression by means of washer 142 which is tightly riveted to the end of the pinion.

Rigidly mounted on pinion 100 is a disc 144 which contacts the outer face of friction plate 134. This friction means is sufficient to make it possible to drive the bolt by means of key 96 and also to permit a slippage of the friction parts when the bolt is operated by means of the hand knob 94. The amount of friction between friction plate 134 and disc 144 may be easily varied by either changing the size or compression of the spring 140.

To conserve space, it will be noted that the disc 144 rests against the housing 74 and serves to maintain the pinion against longitudinal movement. The lock 108 is secured against removal from the outside of the door by means of machine screws 146 which extend through collar 102 and are threaded into boss 148 formed on the inside of plate 118.

The usual operation of the device is as follows: When the tenant is inside the room and desires to operate the door securing device he simply turns the knob 94 to or from the lock position against the friction set up by spring 140. This friction insures the bolt against accidental movement regardless of its position.

When it is desired to move the bolt to engage the extension bar 50 the operator moves it to the intermediate position and then opens the door until the bar drops to the position shown in

dotted lines into notch 62. When so positioned, the parts will secure the door against accidental movement from the partially open position. When it is desired to close the door, bar is slightly lifted and the door then can be moved for closing.

During these operations the lock 108 is in the locked position since the key is removed therefrom and regardless of the number of times that the knob 94 is turned it will not affect the position of the plug in the barrel.

When the tenant leaves the room and desires to lock the door he inserts the key 96 in the lock and turns it to force the bolt 72 to the position shown in dotted lines in Figure 6. He removes the key and on returning to the room can unlock the door by reversing the movement of the bolt 72.

It will be noted that the spring tension of 140 is sufficient to set up sufficient friction between discs 134 and 144 whereby when the lock is manually operated the pinion 100 will be rotated to move the bolt. Should the tenant desire in leaving the room to secure the door in the partially open position, then he simply moves the lock to the intermediate position so that bolt groove 90 will register with bar 50, then the door is moved to the partially open position and the key is turned to either one of its limits and then removed from the lock.

On returning to open the door the door is first closed then the key is turned to operate the plug so that the plug is rotated to move the bolt to the unlocked position.

The modified form shown in Figures 12, 13, 14, and 15 contemplates the provision of a door securing device wherein the bolt 150 is always urged to the locking position by a spring 152 and it is the principal object of this form to provide means whereby the door can not be completely closed from the outside without first inserting the key into the lock to move the bolt to the unlocked position.

The bolt 150 is mounted in the tubular housing 154 and is provided with rack teeth 156 and an annular groove 90 and head 92. The spring 152 is positioned between the inner end of bolt 150 and the inwardly flanged end 158 of housing 154.

The principal difference between lock 160 and the lock shown and described in the preferred form is that the key is removable from the lock only when the plug 162 is in one certain position.

Referring to Figures 14 and 15, it will be noted that the end of pinion 100 is reduced at 164 to receive the collar 166 which is secured thereto by pin 168. This collar has an annular boss 170 which is rotatably mounted in the ring 172 secured to the plug 162 by means of screws 174. Collar 166 is provided with a transversely disposed lug 176 which is adapted to be engaged by the longitudinally disposed tooth 177 integral with a ring 172.

The inner plate 38 of the door jamb housing may be provided with an extension 178 which serves to protect the wood work of the door casing against mutilation by the extended door bolt 150.

The operation of this modified form of securing device is as follows:

As previously stated, the door bolt 150 is normally in the extended or locking position due to the action of compression spring 152. When on the inside of the room the operator may move the bolt to any desired position by means of the

knob 94. Since the bolt 150 is normally in the extended position and the tooth 177 of the lock member is in a fixed position when the key is removed from the lock, it is apparent that lug 6 176 will move away from tooth 177 whenever the bolt is moved inwardly against the action of spring 152 by knob 94.

When the operator is on the outside of the room and the door is locked, he simply inserts 10 the key 180 into the lock and rotates it so as to force tooth 177 against lug 176 to rotate the pinion 100 and move the bolt to the unlocking position. The action of spring 152 will now force 15 the lock plug 162 back to its normal position so that the key can be removed after the door has been opened.

When the tenant leaves the room and desires 20 to maintain the door in the partially open position he moves the bolt so that it will properly register with bar 50, opens the door to the limit of bar 50, turns the key back to normal locking position and removes it from the lock. On returning to open the door, he first closes the door, 25 inserts the key, and operates the bolt 150 to the unlocking position.

It is quite apparent that many modifications 30 may be made without departing from the spirit of this invention and it is desired to be limited only by the scope of the claims.

What we claim as new and desire to be secured by Letters Patent is:

1. In a door securing device an open-edge 35 housing having an inner side wall and an outer side wall and having a bight formed in its outer side wall and being secured to the inside face of the door jamb, a longitudinally slotted extension bar pivotally mounted within said housing by means of a pin engaging the two side walls of said housing above said bight with one end of said 40 bar slot positioned in alignment with said bight, an annularly grooved sliding bolt carried by the door operable by means from either side of the door to cause it to enter said bight and engage in the slot of said extension bar and move said 45 extension bar to the extended position as said door is moved toward the open position, and a spring positioned to urge said bar into said housing and to urge it against said bolt when the bar is extended.

2. In a door securing device a housing secured 50 to the face of the door jamb, an extension bar pivotally mounted at its one end within the two side walls of said housing and having a longitudinal slot formed therethrough, the end portion 55 of said slot adjacent the pivotal point being enlarged and the end of slot at the free end of the bar being offset transversely of the bar, a recess formed in the inner wall of said housing in alignment with the enlarged end of said slot, an 60 annularly grooved bolt slidably mounted in the door and normally urged to the extended position by resilient means whereby the bolt is normally moved into said recess in said inner wall to secure the door in the closed position, a rack 65 formed in the body of said bolt, a pinion in operative relation with said rack and manually operable from both sides of said door whereby said bolt is movable to the various operable positions against the urge of said spring to permit its easy 70 engagement with said extension bar to limit the opening movement of said door.

ALLEN CHAMBERS.
ROY E. GEARHART.
